I. J. BOWMAN

GLARESHIELD

Filed Jan. 5, 1924

Irvin J. Bowman.
By Watson E. Coleman Attorney

UNITED STATES PATENT OFFICE.

IRVIN J. BOWMAN, OF JOHNSTOWN, PENNSYLVANIA.

GLARESHIELD.

Application filed January 5, 1924. Serial No. 684,823.

To all whom it may concern:

- Be it known that I, IRVIN J. BOWMAN, a citizen of the United States, residing at Johnstown, in the county of Cambria and State of Pennsylvania, have invented certain new and useful Improvements in Glareshields, of which the following is a specification, reference being had to the accompanying drawings.
- 10 This invention relates to improvements in glare shields for self-propelled vehicles and has for an important object thereof the provision of a glare shield which is readily attachable to either open or closed cars.
- 15 A further object of the invention is to provide a device of this character which is readily shiftable to operative or inoperative positions and which is automatically held in either of such positions as desired.
- 20 A further object of the invention is to provide in a device of this character means whereby the adjustment of the shield as to its vertical position is readily effected so that the shield may be readily adjusted to accommodate drivers of various heights.
- 25 A still further object of the invention is to provide in a device of this character a novel and improved mounting for the shield which may be very cheaply and readily produced.

30 These and other objects I attain by the construction shown in the accompanying drawings wherein for the purpose of illustration is shown a preferred embodiment of my invention and wherein:

Figure 1 is a front elevation of a glare shield constructed in accordance with my invention;

Figure 2 is a side elevation thereof showing the same applied to the framework of a closed car;

Figure 3 is an enlarged section on the line 3—3 of Figure 2;

Figure 4 is a perspective of the tube showing the manner of constructing the attaching wings thereof;

Figure 5 is a detail section of the upper end of the glare shield showing the manner of applying the same to an open car windshield frame;

Figure 6 is a perspective of the attaching bracket removed showing the slot in which the spring is fastened.

Figure 7 is a side elevation showing a modified adjusting structure for maintain-

ing the supporting rod in adjusted positions.

Referring now more particularly to the drawings, the numeral 10 indicates a shield supporting arm consisting of a rod circular in cross section which is provided at one end with a flattened portion 11 adapted to be engaged between ears 12 of an attaching plate 13 and having a central opening for the reception of a pivot pin 14 extending through and mounted in said ears. This flattened portion is provided upon its periphery with two angularly disposed flattened faces 15 and 16 and the attaching plate 13 has secured thereto a spring 17 for coaction with these surfaces. The spring 17 by bearing against a selective surface holds the rod 10 in a selected position with respect to the attaching plate 13. When the spring is engaged with the surface 15 the rod depends from the attaching plate and lies in substantial parallelism with the windshield. When the surface 16 is engaged by the spring the rod 10 is in substantial alignment with the ears of the bearing plate and is horizontally disposed so that it is above and out of the way of the line of vision of the driver of the vehicle.

The glare shield mounting proper consists of a tube 18 of greater width than the sheet of translucent material 19 which is employed as an anti-glaring device. At one end this tube has secured thereto a transversely extending bar 20 having a longitudinally extending slot 21 directed toward the opposite end of the bar and in this slot is clamped one edge of the sheet 19. In securing the channel bar 20 to the tube 18 I preferably slot the tube longitudinally for a short distance at a point spaced slightly from the end at which the bar is to be disposed and then slot the tube transversely so as to partially sever the same, the transverse slotting being such that two wings 22 are formed by the splitting of the tube along the longitudinal slot. These wings are then engaged with a flange 23 provided upon the bar 20 at a desired point and secured thereto by spot welding, riveting or the like, the former being shown in the present illustration. Through the tube adjacent the opposite end thereof I mount a headed securing element 24 which extends through the sheet 19 adjacent the free edge thereof which secures the same

to the tube. That end of the tube adjacent the securing element projects beyond the sheet a short distance affording a handle by means of which the device may be 5 operated and this end is preferably closed by a cap 25 or the like. Through the bar 20 a securing element 26 is directed which is adapted to clamp against the bar 10 when the same is engaged in the tube to hold the 10 tube in adjusted position upon the bar. By adjusting this screw and shifting the tube upon the bar any desired height of the glare shield element 19 may be attained.

The attaching plate 13 is provided in its 15 ends with openings adapted for the reception of securing elements 27. These securing elements may be in the form of wood screws for attaching the plate directly to the frame-work of a closed car construction 20 or may be bolts such as shown in Figure 5, which bolts extend through clamping elements 28 constructed to engage with and hold the attaching plate in position upon the upper frame member 29 of the wind- 25 shield.

In Figure 7 I have shown a side elevation of the upper end of the supporting rod or arm 10 in which the upper end of the arm is formed to provide a circular head 30 10^a provided in its periphery with notches 10^b. The spring 17 is formed to provide a detent 17^a engaging in these teeth and held in engagement therewith by the resiliency 35 of the spring so that this detent may be engaged with a suitable notch and the arm 10 held in any desired adjusted position. While the arm 10 has been described and disclosed as being preferably circular in 40 form the cross sectional shaping of this arm may be altered as desired, it being merely

necessary that the tube 18 be shaped to conform to the shaping of the arm.

From the foregoing it is believed to be obvious that a glare shield constructed in accordance with my invention may be readily applied to either open or closed cars, 45 may be readily shifted from operative to a selected inoperative position and may have the anti-glare element thereof readily vertically adjusted to accommodate the 50 needs of the driver of the vehicle. It will furthermore be obvious that the construction of the device as hereinbefore set forth is capable of a considerable range of change 55 and modification without in any manner departing from the spirit of my invention and I accordingly do not wish to be understood as limiting myself to such specific structure except as hereinafter claimed.

I claim:—

In an anti-glare device adapted to be supported by the windshield of a vehicle, a bar, a tube receiving the bar at one end and having its opposite end closed, the first named end of the tube having integral 65 transversely disposed oppositely extending wings, a channel bar secured to said wings and having its channel downwardly directed, an anti-glare shield having one edge 70 thereof engaged in the channel of the bar and clamped between the arms of the channel and the lower end thereof secured to the tube adjacent the lower end thereof, and means extending through the tube for 75 clamping the tube in adjusted positions up- on the rod.

In testimony wherof I hereunto affix my signature.

IRVIN J. BOWMAN.
